GUN MOUNT

Joseph M. Colby, United States Army,
Lake Mills, Iowa

Application June 27, 1942, Serial No. 448,825

9 Claims. (Cl. 89—37)

(Granted under the act of March 3, 1883, as
amended April 30, 1928; 370 O. G. 757)

The invention described herein may be manufactured and used by or for the Government for governmental purposes, without the payment to me of any royalty thereon.

This invention pertains to a gun mount and more particularly to a device for mounting a machine gun in an armored structure.

An object of the invention is to provide a semi-flexible mount which will detachably support standard machine guns for conjoint movement in an armored device.

Another object of the invention is to provide a mounting which will permit a quick removal of machine guns therefrom and allow their immediate use on emergency tripods.

The specific nature of the invention as well as other objects and advantages thereof will clearly appear from a description of a preferred embodiment as shown in the accompanying drawings in which:

Fig. 1 is a plan view of a mounting for a pair of machine guns in an armored vehicle or other device,

Fig. 2 is a view of the mounting in side elevation showing a portion of the armored front of a tank or other device,

Fig. 3 is a view of the mount in rear elevation,
Fig. 4 is a sectional view on the line 4—4 of Fig. 1,

Figs. 5 and 6 are respectively plan and side elevational views of the gun cradle,

Fig. 7 is a bottom plan view of a portion of the cradle showing an adapter seat and lock for one of the machine gun pintles,

Fig. 8 is a sectional view on the line 8—8 of Fig. 1 showing additional details of the pintle seat and lock,

Fig. 9 is a plan view of the gun port and socket in a side of an armored device, and

Fig. 10 is a sectional view on the line 10—10 of Fig. 9.

Referring to Figs. 1 and 2, a cradle 1 having a forwardly projecting arm 2 is pivotally secured by a pin assembly 3 adjacent a pair of gun ports 4 in an armored wall 5. The cradle is substantially a Y-shaped member with a pair of rear arms 6, each of which is conditioned to receive the breech portion 7 of a machine gun. The muzzle ends 8 of the barrels 9 rest in transverse bores 10 of cylindrical rotors 10 which are carried on the pin assembly 3 at the gun port 4. The rear of gun cradle 1 is connected through a pivot 11 to a hollow cylindrical plunger 12 which is telescopically mounted in a hollow sleeve 13 pivotally attached to a base 14. A compression spring 15

5 maintains the ends of the plunger 12 and the sleeve 13 in a spaced relationship. This arrangement functions as an equilibrator and counterbalances the cradle for the preponderance of weight at the rear portion of the gun mounting.

Each machine gun is provided with a standard emergency tripod pintle 16 which is secured to the gun by a suitable swivel pin. When a gun is mounted on the cradle 1, the pintle 16 is received in a socket-like adapter seat 17 and locked thereto in a manner which will be described in another part of the specification. A pin 18 carried by a chain 19 which is secured to the rear of the cradle is insertable in apertured lugs 20 on the cradle and a pair of aligned apertures in lugs on the breech portion of the gun thereby fastening the gun to the cradle.

A limited amount of elevation of the guns and their cradle is provided about pivot pin 3. A T-shaped operating lever 21 is secured to a lug 22 on cradle 1 by a pivot pin 23. A rearwardly depending arm 24 on the lever is pivotally attached to a link 25 which is in turn coupled to a collar 26 on the top of the relatively stationary cylinder 13 by a pivot pin 27. Secured to an ear 28 on the cradle proper by suitable means is a fixed quadrant rack 29. A rigid horizontal grip element 30 and a pivoted grip element 31 are situated on the free end of the operating lever 21. A rod 32 is arranged to slide through a pair of aligned bores 33 and 34 in the fixed grip and a lug 35 on the lever arm respectively. A toothed pawl 36 is secured to the lower end of the rod which projects beyond the lug 35. Intermediate the grip and the lug is a coiled spring 37 which is in compression and bears on a fixed enlarged shoulder 38 on the rod and also against the top face of the lug 35. This normally separates the two grip elements 30 and 31 as shown in Figs. 1 and 3 and holds the toothed pawl 36 in engagement with the teeth of the quadrant rack 29 thereby securing the cradle in a selected position.

An ammunition chute 39 and a stand 40 for ammunition trays are provided on the gun mount to feed both of the guns from the left hand side.

Referring to Figs. 7 and 8, each adapter seat 17 for a machine gun pintle 16 is provided with a spring urged latch element 41 which is reciprocable in a guide member 42 that is secured to the lower surface of each arm 6 of the cradle. An arcuate end 43 is provided on each element 41 so that it will slip into an annular retaining groove 44 on a pintle. A pair of springs 45 urge the latch element toward the axis of the adapter

seat 17 and retain the pintle in its seat. A cam lever 46 having a cam face 46' is pivoted at 47 on the latch and is employed to retract the latch element 41 against the resistance of the springs thereby permitting the pintle to be unlocked and withdrawn from its seat.

The pair of gun ports 4 in the armor 5 are provided with a multi-socket structure 48, see Figs. 9 and 10. A pair of spaced cylindrical sockets or journals 49 are provided with front and rear openings 50 and 51 respectively and are adapted to receive the hollow rotors 10 which support the gun muzzles 8. Intermediate the sockets is a chamber 52 which is adapted to receive the extreme end of the forwardly extending arm 2 of the gun cradle which carries the pin 3. The pin is arranged to rotate in a bore 53 in the end of the arm and is secured against the lateral displacement by a screw 54 which rides in a groove 55 in the pin (see Fig. 1). The journals 49 are provided with open ends which are in a plane perpendicular to the axes of the rotors 10, thereby permitting the insertion of the rotors. The front and rear openings 50 and 51 are not sufficiently large to permit the withdrawal of the rotors (see Fig. 10).

The cradle is mounted at the gun ports as follows: The front end of arm 2 is inserted in chamber 52 and then the pin 3 is inserted in bore 53 and secured against axial movement by screw 54. The rotors are slipped into the journals from the side of the housing 48 and are press fitted on to the ends of pin 3. The cradle 1 is now pivotally attached to the socket structure 48 on the armored wall 5 of the tank or other device.

The attachment of the guns in the mounting and its operation is as follows: The gun muzzles 8 are inserted in the bores 10' of the rotors 10 and then the breech ends of the guns are lowered until the pintles 16 are in alignment with their corresponding adapter seats 17. Pressure on the breech portions of the gun forces the pintles into the seats where they are secured by the spring pressed latch elements 41 which lodge in the retaining grooves 44. Pin 18 is then slipped into the aligned apertures in the lugs 20 on the cradle and the fastening lugs on the lower rear of the gun. The gun and its mount are now ready for use.

The cradle is pivoted for elevation about an axis through the pin 3 adjacent the gun ports 4. By squeezing the grip elements 30-31 the gunner is able to release the toothed pawl 36 from engagement with the quadrant rack 29. Lever 21 may now be oscillated about pivot 23 as an axis. When the lever is depressed, the lazy tong arrangement composed of arm 24 and link 25 is crushed. This lowers the rear end of the cradle and pushes the plunger 12 into the sleeve 13 against the resistance of spring 15. When the gun is elevated the required extent, the grips 30-31 are released and the pawl 36 engages the rack 29 thereby locking the gun against movement. Similar manipulations of the grips and a slight upward force on the lever arm 21 will depress the gun muzzle. With this arrangement the guns and the cradle are quickly and easily controlled by a single gunner.

Occasions sometimes arise when it is desired to remove the machine guns from the armored device and mount them on emergency tripods. The release of two simple latches and two pins permits instant withdrawal of the guns from their cradle. Each gun may be quickly mounted on a tripod by placing its pintle in a

supporting socket on the tripod. Thus a standard machine gun may be expeditiously employed alternatively in the instant mount or on an emergency tripod without the use of any additional special fittings. There results a saving in time and material and an increased efficiency from a military standpoint.

I claim:

1. In a mounting for a gun, a cradle pivoted at one end to a support, an equilibrator on said support and coupled to the other end of said cradle, articulated linkage between said cradle and said equilibrator, and adjustable means interconnecting said linkage and said cradle for selectively retaining said cradle in a plurality of positions about its pivot.
2. In a mounting for a gun, a cradle pivoted at one end to a support, an equilibrator on said support and coupled to the other end of said cradle, a lever pivoted on said cradle, a rigid projecting arm on said lever intermediate the ends thereof, a link pivotally coupled to the outer end of said arm and to said equilibrator, a toothed rack on said cradle, a movable pawl on said lever for selective engagement with said rack when said lever is swung about its pivot, and means on said lever for controlling the engagement of said pawl, said lever adapted for elevating or depressing said mounting.
3. In a gun mounting, a cradle pivoted at one end to a support, an equilibrator on said support and coupled to the other end of said cradle, articulated linkage between said cradle and said equilibrator, adjustable means interconnecting said linkage and said cradle for selectively retaining said cradle in a plurality of positions about its pivot, and means on said cradle for securing a gun thereto.
4. In a mounting for a gun, a cradle pivoted at one end to a support, an equilibrator on said support and coupled to the other end of said cradle, a lever pivoted on said cradle, a rigid projecting arm on said lever intermediate the ends thereof, a link pivotally coupled to the outer end of said arm and to said equilibrator, a toothed rack on said cradle, a movable pawl on said lever for selective engagement with said rack when said lever is swung about its pivot, a pivoted grip on the free end of said lever for controlling the engagement of said pawl, means interconnecting said pawl and said grip, and means normally maintaining said pawl in engagement with said rack whereby said lever is locked against movement, said lever adapted for elevating or depressing said mounting.
5. In a mounting for a pair of guns, a cradle pivoted at one end to a support, said support having gun ports arranged to sustain a pair of gun barrels, an equilibrator on said support coupled to the other end of said cradle, articulated linkage between said cradle and said equilibrator, and adjustable means interconnecting said linkage and said cradle for selectively retaining said cradle in a plurality of positions about its pivot.
6. In a mounting for a gun, a support having a gun port, a hollow member rotatably mounted in said support at said gun port, said member being adapted to receive a gun barrel, a cradle pivoted at one end to said support on an axis coinciding with the axis of said member, an equilibrator on said support coupled to the other end of said cradle, articulated linkage between said cradle and said equilibrator, and adjustable means interconnecting said linkage and said cradle for

selectively retaining said cradle in a plurality of positions about its pivot.

7. In a mounting for a gun, a support having a gun port, a hollow member rotatably mounted in said support at said gun port, said member being adapted to receive a gun barrel, a cradle pivoted at one end to said support on an axis coinciding with the axis of said member, an equilibrator on said support and coupled to the other end of said cradle, a lever pivoted on said cradle, a rigid projecting arm on said lever intermediate the ends thereof, a link pivotally coupled to the outer end of said arm and to said equilibrator, a toothed rack on said cradle, a movable pawl on said lever for selective engagement with said rack when said lever is swung about its pivot, a pivoted grip on the free end of said lever for controlling the engagement of said pawl, means interconnecting said pawl and said grip, and means normally maintaining said pawl in engagement with said rack whereby said lever is locked against movement, said lever being adapted for movement elevating or depressing said mounting about its pivot.

8. In a mounting for a gun, a supporting structure, a cradle pivoted at one end to said structure, a lever pivoted on said cradle, articulated linkage connecting said lever to said structure, a toothed rack on said cradle, a movable pawl on said lever for selective engagement with said rack when said lever is swung about its pivot, and means on said lever for controlling the engagement of said pawl, whereby said lever is adapted to elevate or depress said mounting.

9. In a mounting for a gun, a supporting structure, a cradle pivoted at one end to said structure, a lever pivoted on said cradle, a rigid projecting arm on said lever intermediate the ends thereof, a link pivotally coupled to the outer end of said arm and to said structure, a toothed rack on said cradle, a movable pawl on said lever for selective engagement with said rack when said lever is swung about its pivot, and means on said lever for controlling the engagement of said pawl, whereby said lever is adapted to elevate or depress said mounting.

JOSEPH M. COLBY.
